UNITED STATES PATENT OFFICE

150,922

DESIGN FOR A COMBINED RADIO CABINET, CLOCK, AND LAMP

Albert C. Black, Los Angeles, Calif.

Application February 11, 1947, Serial No. 136,830

Term of patent 3½ years

(Cl. D56—4)

To all whom it may concern:

Be it known that I, Albert C. Black, a citizen of the United States, residing at Los Angeles, in the county of Los Angeles and State of California, have invented a new, original, and ornamental Design for a Combined Radio Cabinet, Clock, and Lamp, of which the following is a specification, reference being had to the accompanying drawing, forming part thereof.

The figure is a perspective view of a combined radio cabinet, clock, and lamp, showing my new design.

I claim:

The ornamental design for a combined radio cabinet, clock, and lamp, as shown.

ALBERT C. BLACK.
